H. M. Kolbe Co., Inc., New York, N. Y., a corporation of New York

Application July 30, 1954, Serial No. 31,680

Term of patent 3½ years

(Cl. D92—1)

To all whom it may concern:

Be it known that I, William L. Kolbe, a citizen of the United States of America, residing at Hewlett Harbor, Long Island, county of Nassau, and State of New York, have invented a new, original, and ornamental Design for a Textile Fabric or Similar Article, of which the following is a specification, reference being had to the accompanying drawing, forming part thereof.

The figure is a plan view of a textile fabric showing the complete width of my design. The dot and dash lines on the drawing outline substantially the design unit, which unit is repeated in regular succession as indicated by the extensions beyond the unit boundaries,

I claim:

The ornamental design for a textile fabric or similar article, substantially as shown and described.
